PROCESS FOR REFINING HYDROCARBON OILS BY MEANS OF ORGANIC OXIDES

Ernst Terres, Berlin, Germany, and Josef Moos, New York, and Erich Saegerbarth, Jackson Heights, N. Y., assignors to Edeleanu Gesellschaft, m. b. H., a corporation of Germany

No Drawing. Application October 25, 1937, Serial No. 170,971. In the Netherlands March 20, 1936

9 Claims. (Cl. 196—13)

This invention relates to the refining of hydrocarbon oils, such as mineral oils, coal tar or bituminous coal tar oils, by means of selective solvents which have the characteristics of dissolving certain undesirable fractions present in hydrocarbon oils for producing oils suitable for lubrication purposes, and is a continuation in part of our application Serial No. 12,527, filed March 22, 1935, for Processes for refining hydrocarbon oils by means of ketones, organic acids, organic anhydrides, organic oxides, alcohols and ethers.

Although not much is known about the actual constitution of the individual components present in hydrocarbon oils, it is understood that the cuts or fractions which are heavy enough for lubricating stock contain representatives of the aromatic, hydroaromatic and unsaturated groups which are undesirable for lubricating purposes.

The removal of these undesirable components, which are generally referred to as "low viscosity index hydrocarbons" or "non-paraffinic constituents", by means of suitable selective solvents leaves an undissolved fraction which contains mainly paraffin-like components. These undissolved fractions or raffinates are identified by greatly improved physical and chemical specifications, such as gravity, viscosity temperature relationship, Conradson carbon and resistance against oxidation, and they are generally referred to as "high viscosity index hydrocarbons" or "paraffinic constituents".

We have found that cyclic organic oxides have very good selective solvent action upon hydrocarbon oils. These cyclic oxides comprise ethylene oxide, propylene oxide and mixtures thereof, which dissolve the undesirable fractions of hydrocarbon oils as described above and produce a greatly improved raffinate. In the claims, this class of selective solvents is referred to as "cyclic organic oxides containing one oxygen atom and less than four carbon atoms per molecule." In carrying out our invention, we contact one or the other of these selective solvents with the hydrocarbon oil to be treated in batch or in counter-current using a mixing and settling equipment or a tower mixer.

The effect of our solvents upon mineral oils may be seen from the following example:

A dewaxed Mid-Continent heavy motor oil was extracted at 32° F. with ethylene oxide and this extraction was carried out with 300% solvent added in three batches of 100% each. The raffinate and extract layers were separated from each other and the results after recovering the

solvent from the raffinate and extract solutions are shown in the following table:

	Original oil (Mid-Cont. lub. dis- tillate)	Raffinate	Extract	5
Yields percent by volume.....	100	60	40	
A. P. I. gravity.....	23.0	27.7	16.5	
Saybolt viscosity at 100° F.....	1379	824	.....	10
Saybolt viscosity at 210° F.....	93.4	79.2	.....	
V. I.	73.7	94	.....	

Instead of employing ethylene oxide or propylene oxide alone, we may use them mixed together, and we may use them either alone or mixed together in presence of representatives of three different classes of auxiliary solvents. The members of class 1 of the auxiliary solvents, to which belong the aromatics, hydroaromatics, the non-selective aliphatic and aromatic halogen derivatives, the non-selective ketones, esters and ethers, serve to increase the solvent power of our above mentioned selective solvents.

The members of class 2 of the auxiliary solvents, to which belong the alcohols and organic acids, have the purpose of decreasing the solvent power of the ethylene oxide and propylene oxide.

The members of class 3 of the auxiliary solvents, to which belong for example the low boiling members of the paraffines, for instance propane, butane or mixtures thereof, have the purpose of increasing the selectivity of our selective solvents.

Instead of recovering the solvents by distillation, we may employ a different solvent which dissolves only the solvents but not the hydrocarbon fractions. From the solvent mixture containing the additional solvent, and our selective and auxiliary solvents, we may remove the additional solvent either by distillation or by the addition of water or other agents which cause it to become insoluble in our selective and auxiliary solvents.

Other scopes of our invention and the action of the auxiliary solvents is explained in our co-pending applications Serial Nos. 12,526, 12,528 and 12,529, filed March 22, 1935.

We claim the following as our invention:

1. A process of refining mineral oil containing both high viscosity index hydrocarbons and low viscosity index hydrocarbons, comprising extracting the oil with a selective solvent of the class consisting of cyclic organic oxides containing one oxygen atom and less than four carbon atoms

50
55

per molecule, to form a raffinate layer containing the high viscosity index hydrocarbons, and an extract layer containing the low viscosity index hydrocarbons of said mineral oil dissolved in said selective solvent, separating said layers from each other and recovering the solvent therefrom.

2. In a process of refining hydrocarbon oil by solvent treatment, the step of extracting said hydrocarbon oil with a substance of the class consisting of cyclic organic oxides containing one oxygen atom and less than four carbon atoms per molecule, said substance functioning as a selective solvent, to cause the separation of the low viscosity index constituents from the high viscosity index constituents of the oil.

3. A process of refining mineral oil containing both high viscosity index hydrocarbons and low viscosity index hydrocarbons, comprising extracting the oil with ethylene oxide as a selective solvent to form a raffinate layer containing the high viscosity index hydrocarbons, and an extract layer containing the low viscosity index hydrocarbons of said mineral oil dissolved in the ethylene oxide, separating said layers from each other and recovering the solvent therefrom.

4. In a process of refining hydrocarbon oils by solvent treatment, the step of extracting the oil with ethylene oxide, as a selective solvent to cause the separation of the low viscosity index constituents from the high viscosity index constituents of the oil.

5. In a process of refining hydrocarbon oils by solvent treatment, the step of extracting the oil with a mixture of propylene oxide and ethylene oxide, said mixture functioning as a selective solvent to cause the separation of the low viscosity index constituents from the high viscosity index constituents of the oil.

6. A process of refining mineral oil containing both high viscosity index hydrocarbons and low viscosity index hydrocarbons, comprising extracting the oil with propylene oxide as a selective solvent to form a raffinate layer containing the high viscosity index hydrocarbons, and an extract layer containing the low viscosity index hydrocarbons of said mineral oil dissolved in the propylene oxide, separating said layers from each other and recovering the solvent therefrom.

7. In a process of refining hydrocarbon oils by solvent treatment, the step of extracting the oil with propylene oxide, as a selective solvent to cause the separation of the low viscosity index constituents from the high viscosity index constituents of the oil.

8. A process of refining a hydrocarbon oil comprising extracting the oil with a substance of the class of cyclic organic oxides containing one oxygen atom and less than four carbon atoms per molecule, as a selective solvent, at such temperatures as to produce a separation into two liquid phases containing respectively paraffinic and non-paraffinic constituents, separating the phases from each other and recovering the solvent therefrom.

9. A process of refining a hydrocarbon oil comprising mixing the oil with a substance of the class of cyclic organic oxides containing one oxygen atom and less than four carbon atoms per molecule, as a selective solvent, and adjusting the temperature to produce a separation into two oil containing phases, separating the phases from each other and recovering the solvent therefrom.
